SIGNAL GESELLSCHAFT M. B. H., OF KIEL, GERMANY.

MULTIPLE-CONTACT MICROPHONE.

1,315,337.

Specification of Letters Patent.

Patented Sept. 9, 1919.

Application filed February 24, 1916, Serial No. 80,190. Renewed December 2, 1918. Serial No. 265,051.

To all whom it may concern:

Be it known that I, WILHELM KARL JOSEF RUDOLPH, a subject of the German Emperor, and residing at Kiel, county of Schleswig-Holstein, State of Prussia, Germany, have invented certain new and useful Improvements in Multiple-Contact Microphones, of which the following is a specification.

The invention relates to multiple-contact microphones of the type wherein the prejudicial effect of polar forces acting upon the granular filling, and the agglomeration of the carbon grains resulting from said effect shall be avoided by the carbon room being subdivided in a plurality of compartments or cells by means of an intermediate piece of more or less elastic material.

Arrangements of this kind are known in many forms, but, the arrangements hitherto used leave much to be desired with regard to the safety of effectiveness and to the damping of the microphone.

According to the invention, the desired object is obtained free from objections by using for the subdivision of the carbon room an intermediate piece of velour cloth (velvet or plush) the hairs of which may as far as possible lie in the same direction and are, without exception, inclined to the plane of the ground cloth or of the electrodes. In order to avoid fringing the cloth during the shaping of the same, and to prevent carefully the jutting out of coarse threads, the cloth piece may previously be gummed on to a thin lining consisting of a homogeneous material, for example of paper or the like, which after the shaping is terminated serves for fixing the intermediate piece on to one of the electrodes.

In this manner, with a nearly complete utilization of the space available between the electrodes, a very elastic subdivision of the filling room is obtained, which not only continually loosens the granular filling on the cessation of the jerks but also allows the microphone damping to be reduced at will. That is to say, one can vary the damping continuously, by changing the distance between the electrodes, without at the same time finding it necessary to change the length of the little hairs which are all inclined in the same way to the electrode. When the distance between the electrodes is made less, the hairs as a whole, uniformly

assume a greater inclination to the plane of said electrodes, and vice versa.

According to the invention, a particular advantageous operation is further obtained with microphones having a filling of granules of different sizes and weights by the feature that the hairs of the cloth which is used for the subdivision of the carbon room, allow, without injurious consequences from the damping of the microphone, the granular filling to be strictly separated in layers of finest and gradually increasing grains and of grains of different specific weight, the upper layers of fine or light grains thus being prevented from mixing with the lower layers of the coarser or heavier grains. In that manner there is obtained a continued remarkable sensitiveness of the microphone to sounds of different frequencies which thus may be rendered as true to nature as possible. With the same thickness of grains the difference in weight may be obtained, for example, by using metal grains or hollow balls or generally grains of different specific weight which are coated with carbon or another material of suitable conductivity. Ordinarily it may be sufficient to employ carbon grains of varying sizes.

In the accompanying drawings, an embodiment of the invention is represented by way of an example. Figure 1 is a plan view of a grid shaped intermediate piece illustrating the principle of the invention; Fig. 2 shows a central sectional elevation of microphone electrodes provided with said intermediate piece; Fig. 3 represents a central sectional elevation of a microphone constructed according to the invention, the carbon room being subdivided into a plurality of compartments filled with grains of different sizes.

In the drawings *a* designates a grid shaped intermediate piece formed of velour cloth and provided with a lining *b* of paper gummed on to the rear side of the ground cloth before the piece is shaped. With the aid of the said lining *b* the piece *a* is gummed on to the electrode *c* of the microphone. The hairs *h* of the intermediate piece are inclined in the same direction to the plane of the ground cloth so as to project obliquely upward or downward and to touch the second electrode *d* of the microphone. The hairs *h* hold in elastic sus-

2
pension the granular filling *e* contained in the cells which are formed by the grid shaped piece *a*. Careful attention is to be paid to having as much as possible all 5 of the hairs inclined in the same direction, in order to avoid disturbing their uniformity when regulating the damping of the microphone.

It will be observed that when the hairs 10 are inclined to the faces of the electrodes as in the present invention, a very elastic and therefore a very efficient damping of the microphone is secured. As the distance between the electrodes is made greater or 15 less, the hairs are pressed against the electrode to a less or greater extent respectively, thus regulating the damping. At the same time the hairs remain in their original uniform arrangement with respect to one another. 20

Corresponding to Fig. 3, the cells which are formed between the electrodes *c* and *d* by the intermediate piece *a* are filled with carbon granules *e* of different thickness and 25 weight, increasing by compartments from the top to the bottom. In this way sounds of different character may be received and rendered as true to nature as possible by a suitable diaphragm *g* coupled with the 30 electrode *d*.

What I claim is:

1. A granular microphone having its filling room subdivided into a plurality of compartments by means of velour cloth, said 35 cloth having its bottom portion fixed to one of the electrodes and the fine hair or top portion touching the other electrode of said microphone.

2. A granular microphone having its filling room subdivided into a plurality of compartments by means of velour cloth, said cloth having its bottom portion fixed to one of the electrodes and the fine hair or top portion touching the other electrode of said 45 microphone, the ground warp of said cloth being fixed to a lining of homogeneous material such as paper, so as to prevent fringing.

3. A granular microphone having its filling room subdivided into a plurality of compartments by means of velour cloth, said cloth having its bottom portion fixed to one of the electrodes and the fine hair or top portion touching the other electrode of 55 said microphone, the ground warp of said cloth being fixed to a lining of homogeneous material such as paper, before shaping the cloth, so as to prevent fringing.

4. A granular microphone having its filling room subdivided into a plurality of compartments by means of velour cloth the hairs of which are inclined in the same direction to the plane of the ground warp and of the electrodes. 60

5. A granular microphone having its fill-

ing room subdivided into a plurality of compartments by means of velour cloth the ground warp of which is fixed to a lining of homogeneous material such as paper and the hairs of which are inclined in the same 70 direction to the plane of the ground warp and of the electrodes.

6. A granular microphone having its filling room subdivided into a plurality of compartments by means of velour cloth the 75 ground warp of which is fixed to a lining of homogeneous material such as paper before shaping said cloth the hairs of which are inclined in the same direction to the plane of the ground warp and of the electrodes. 80

7. A granular microphone having between the electrodes intermediate strips consisting of velour cloth said strips subdividing the filling room of the microphone into a plurality of compartments. 85

8. A granular microphone having between the electrodes intermediate strips consisting of velour cloth the hairs of which are inclined in the same direction to the plane of 90 the ground warp and of the electrodes, said strips subdividing the filling room of the microphone into a plurality of compartments.

9. A granular microphone having between 95 the electrodes, intermediate strips consisting of velour cloth, said cloth having its bottom portion fixed to one of the electrodes and the fine hair or top portion touching the other electrode, the ground warp of said cloth being fixed to a lining of homogeneous material so as to prevent fringing, said strips subdividing the filling room of the microphone into a plurality of compartments. 100

10. A granular microphone having between 105 the electrodes intermediate strips consisting of velour cloth, said cloth having its bottom portion fixed to one of the electrodes and the fine hair or top portion touching the other electrode, the ground warp of said cloth 110 being fixed to a lining of homogeneous material before shaping the strips, so as to prevent fringing, said strips subdividing the filling room of the microphone into a plurality of compartments. 115

11. A granular microphone having between the electrodes intermediate strips consisting of velour cloth, the ground warp of which is fixed to a lining of homogeneous material, and the hairs of which are inclined 120 in the same direction to the plane of the ground warp, said strips subdividing the filling room of the microphone into a plurality of compartments.

12. A granular microphone having between 125 the electrodes intermediate strips consisting of velour cloth the ground warp of which is fixed to a lining of homogeneous material before shaping the said strips the hairs of which are inclined in the same di- 130

rection to the plane of the ground warp, said strips subdividing the filling room of the microphone into a plurality of compartments.

5 13. A granular microphone having its filling room subdivided into a plurality of compartments by means of a grid-shaped intermediate piece consisting of one piece of velour cloth, said cloth having its bottom portion fixed to one of the electrodes and its fine hair or top portion touching the other electrode of said microphone.

10 14. A granular microphone having its filling room subdivided into a plurality of compartments by means of a grid-shaped intermediate piece consisting of one piece of velour cloth, said cloth having its bottom portion fixed to one of the electrodes and its fine hair or top portion touching the other electrode of said microphone, the ground warp of said cloth being fixed to a lining of homogeneous material such as paper, so as to prevent fringing.

15 15. A granular microphone having its filling room subdivided into a plurality of compartments by means of a grid-shaped intermediate piece consisting of one piece of velour cloth, said cloth having its bottom portion fixed to one of the electrodes and its fine hair or top portion touching the other electrode of said microphone, the ground warp of said cloth being fixed to a lining of homogeneous material such as paper, before shaping the intermediate piece, so as to prevent fringing.

20 16. A granular microphone having its filling room subdivided into a plurality of compartments by means of a grid shaped intermediate piece consisting of one piece of velour cloth the hairs of which are inclined in the same direction to the plane of the ground warp and of the electrodes.

25 17. A granular microphone having its filling room subdivided into a plurality of compartments by means of a grid shaped intermediate piece consisting of one piece of velour cloth having its ground warp gummed on to a lining of homogeneous material and its hairs inclined in the same direction to the plane of the ground warp and of the electrodes.

30 18. A granular microphone having its filling room subdivided into a plurality of compartments by means of a grid shaped intermediate piece consisting of one piece of velour cloth having its ground warp gummed on to a lining of homogeneous material before shaping the intermediate piece the hairs of which are inclined in the same direction to the plane of the ground warp and of the electrodes.

35 19. A granular microphone having its filling room subdivided into a plurality of compartments by means of a grid-shaped intermediate piece consisting of one piece of ve-

lour cloth, said cloth having its bottom portion fixed to one of the electrodes and the fine hair or top portion touching the other electrode of said microphone, the edge strip of said intermediate piece surrounding the filling room.

40 20. A granular microphone having its filling room subdivided into a plurality of compartments by means of a grid-shaped intermediate piece consisting of one piece of velour cloth, said cloth having its bottom portion fixed to one of the electrodes and its fine hair or top portion touching the other electrode of said microphone, the ground warp of said cloth being fixed to a lining of homogeneous material so as to prevent fringing, the edge strip of said intermediate piece surrounding the filling room.

45 21. A granular microphone having its filling room subdivided into a plurality of compartments by means of a grid-shaped intermediate piece consisting of one piece of velour cloth, said cloth having its bottom portion fixed to one of the electrodes, and its fine hair or top portion touching the other electrode of said microphone, the ground warp of said cloth being fixed to a lining of homogeneous material before shaping the intermediate piece, so as to prevent fringing, the edge strip of said intermediate piece surrounding the filling room.

50 22. A granular microphone having its filling room subdivided into a plurality of compartments by means of a grid shaped intermediate piece consisting of one piece of velour cloth the hairs of which are inclined in the same direction to the plane of the ground warp and of the electrodes, the edge strip of said intermediate piece surrounding the filling room.

55 23. A granular microphone having its filling room subdivided into a plurality of compartments by means of a grid shaped intermediate piece consisting of one piece of velour cloth having its ground warp gummed on to a lining of homogeneous material and its hairs inclined in the same direction to the plane of the ground warp and of the electrodes, the edge strip of said intermediate piece surrounding the filling room.

60 24. A granular microphone having its filling room subdivided into a plurality of compartments by means of a grid shaped intermediate piece consisting of one piece of velour cloth having its ground warp gummed on to a lining of homogeneous material before shaping the intermediate piece the hairs of which are inclined in the same direction to the plane of the ground warp and of the electrodes, the edge strip of said intermediate piece surrounding the filling room.

65 25. A granular microphone having its filling room subdivided into a plurality of compartments by means of velour cloth,

said cloth having its bottom portion fixed to one of the electrodes and its fine hair or top portion touching the other electrode of said microphone, the different compartments being filled with grains of different volume and of different weight.

26. A granular microphone having its filling room subdivided into a plurality of compartments by means of velour cloth, 10 said cloth having its bottom portion fixed to one of the electrodes and its fine hair or top portion touching the other electrode of said microphone, the ground warp of said cloth being fixed to a lining of homogeneous material so as to prevent fringing, 15 the different compartments being filled with grains of different volume and of different weight.

27. A granular microphone having its 20 filling room subdivided into a plurality of compartments by means of velour cloth, said cloth having its bottom portion fixed to one of the electrodes and its fine hair or top portion touching the other electrode 25 of said microphone, the ground warp of said cloth being fixed to a lining of homogeneous material before shaping the cloth, so as to prevent fringing, the different compartments being filled with grains of different volume and of different weight.

28. A granular microphone having its filling room subdivided into a plurality of compartments by means of velour cloth the hairs of which are inclined in the same direction 35 to the plane of the ground warp and of the electrodes, the said compartments being filled with grains of different volume and of different weight.

29. A granular microphone having its filling room subdivided into a plurality of compartments by means of velour cloth the ground warp of which is fixed to a lining of homogeneous material and the hairs of which are inclined in the same direction to 45 the plane of the ground warp and of the electrodes, the said compartments being filled with grains of different volume and of different weight.

30. A granular microphone having its filling room subdivided into a plurality of compartments by means of velour cloth the ground warp of which is fixed to a lining of homogeneous material before shaping the cloth the hairs of which are inclined in the same direction to the plane of the ground warp and of the electrodes, the said compartments being filled with grains of different volume and of different weight.

31. A granular microphone having between the electrodes intermediate strips 60 consisting of velour cloth, said cloth having its bottom portion fixed to one of the electrodes and its fine hair or top portion touching the other electrode, said strips subdividing the filling room of the microphone into a plurality 65

of compartments, the different compartments being filled with grains of different volume and of different weight.

32. A granular microphone having between the electrodes intermediate strips 70 consisting of velour cloth, said cloth having its bottom portion fixed to one of the electrodes and its fine hair or top portion touching the other electrode, the ground warp of said cloth being fixed to a lining of homogeneous material so as to prevent fringing, 75 said strip subdividing the filling room of the microphone into a plurality of compartments, the different compartments being filled with grains of different volume 80 and of different weight.

33. A granular microphone having between the electrodes intermediate strips consisting of velour cloth, said cloth having its bottom portion fixed to one of the electrodes 85 and its fine hair or top portion touching the other electrode, the ground warp of said cloth being fixed to a lining of homogeneous material before shaping the strips, so as to prevent fringing, said strips subdividing the filling room of the microphone into a plurality of compartments, the different compartments being filled with grains of different volume and of different weight. 90

34. A granular microphone having between the electrodes intermediate strips consisting of velour cloth the hairs of which are inclined in the same direction to the plane of the ground warp and of the electrodes, said strips subdividing the filling 100 room of the microphone into a plurality of compartments, and the different compartments being filled with grains of different volume and of different weight. 95

35. A granular microphone having between the electrodes intermediate strips consisting of velour cloth the ground warp of which is gummed on to a lining of homogeneous material, and the hairs of which are inclined in the same direction to the plane 110 of the ground warp and of the electrodes, said strips subdividing the filling room of the microphone into a plurality of compartments, and the said compartments being filled with grains of different volume and of different weight. 115

36. A granular microphone having between the electrodes intermediate strips consisting of velour cloth the ground warp of which is gummed on to a lining of homogeneous material before shaping the strips the hairs of which are inclined in the same direction to the plane of the ground warp and of the electrodes, said strips subdividing the filling room of the microphone into a plurality of compartments, and the said compartments being filled with grains of different volume and of different weight. 120

37. A granular microphone having its filling room subdivided into a plurality of 125 compartments, the different compartments being filled with grains of different volume and of different weight. 130

compartments by means of a grid-shaped intermediate piece consisting of one piece of velour cloth, said cloth having its bottom portion fixed to one of the electrodes and 5 its fine hair or top portion touching the other electrode of said microphone, the different compartments being filled with grains of different volume and of different weight.

38. A granular microphone having its 10 filling room subdivided into a plurality of compartments by means of a grid-shaped intermediate piece consisting of one piece of velour cloth, said cloth having its bottom portion fixed to one of the electrodes and 15 its fine hair or top portion touching the other electrode of said microphone, the ground warp of said cloth being fixed to a lining of the homogeneous material, so as to prevent fringing, the different compartments 20 being filled with grains of different volume and of different weight.

39. A granular microphone having its filling room subdivided into a plurality of compartments by means of a grid-shaped intermediate piece consisting of one piece of velour cloth, said cloth having its bottom portion fixed to one of the electrodes and 25 its fine hair or top portion touching the other electrode of said microphone, the ground warp of said cloth being fixed to a lining of homogeneous material so as to prevent 30 fringing, the different compartments being filled with grains of different volume and of different weight.

40. A granular microphone having its filling room subdivided into a plurality of compartments by means of a grid shaped intermediate piece consisting of one piece 40 of velour cloth the hairs of which are inclined in the same direction to the plane of the ground warp and of the electrodes, and the said compartments being filled with grains of different volume and of different 45 weight.

41. A granular microphone having its filling room subdivided into a plurality of compartments by means of a grid shaped intermediate piece consisting of one piece 50 of velour cloth having its ground warp gummed on to a lining of homogeneous material and its hairs inclined in the same direction to the plane of the ground warp and of the electrodes, the said compartments 55 being filled with grains of different volume and of different weight.

42. A granular microphone having its filling room subdivided into a plurality of compartments by means of a grid shaped intermediate piece consisting of one piece of 60 velour cloth having its ground warp gummed on to a lining of homogeneous material before shaping the intermediate piece the hairs of which are inclined in the same 65 direction to the plane of the ground warp and

of the electrodes, the said compartments being filled with grains of different volume and of different weight.

43. A granular microphone having its filling room subdivided into a plurality of 70 compartments by means of a grid-shaped intermediate piece consisting of one piece of velour cloth, said cloth having its bottom portion fixed to one of the electrodes and its fine hair or top portion touching the other 75 electrode of said microphone, the edge strip of said intermediate piece surrounding the filling room, and the different compartments being filled with grains of different volume and of different weight.

44. A granular microphone having its filling room subdivided into a plurality of compartments by means of a grid-shaped intermediate piece consisting of one piece of velour cloth, said cloth having its bottom 80 portion fixed to one of the electrodes and its fine hair or top portion touching the other electrode of said microphone, the ground warp of said cloth being fixed to a lining of homogeneous material so as to prevent 85 fringing, the edge strip of said intermediate piece surrounding the filling room, and the different compartments being filled with grains of different volume and of different weight.

45. A granular microphone having its filling room subdivided into a plurality of compartments by means of a grid-shaped intermediate piece consisting of one piece of velour cloth, said cloth having its bottom portion fixed to one of the electrodes and its fine hair or top portion touching the other electrode of said microphone, the ground warp of said cloth being fixed to a lining of homogeneous material before 100 shaping the intermediate piece, so as to prevent fringing, the edge strip of said intermediate piece surrounding the filling room and the different compartments being filled with grains of different volume and of different weight.

46. A granular microphone having its filling room subdivided into a plurality of compartments by means of a grid shaped intermediate piece consisting of one piece of velour cloth the hairs of which are inclined in the same direction to the plane of the ground warp and of the electrodes, the edge strip of said intermediate piece surrounding the filling room, and the said compartments being filled with grains of different volume and of different weight.

47. A granular microphone having its filling room subdivided into a plurality of compartments by means of a grid shaped intermediate piece consisting of one piece of velour cloth the ground warp of which is gummed on to a lining of homogeneous material so as to prevent fringing and the hairs of which are inclined in the same direction
